Attorney.

UNITED STATES PATENT OFFICE.

JACOB S. ERICKSON, OF CHICAGO, ILLINOIS, ASSIGNOR TO FERGUSON AND LANGE FOUNDRY COMPANY, OF CHICAGO, ILLINOIS, A CORPORATION OF ILLINOIS.

WATER-HEATING APPARATUS.

Application filed January 21, 1924. Serial No. 687,444.

To all whom it may concern:

Be it known that I, JACOB S. ERICKSON, a citizen of the United States, residing at Chicago, in the county of Cook and State 5 of Illinois, have invented certain new and useful Improvements in Water-Heating Apparatus, of which the following is a specification.

My invention relates to apparatus for 10 heating water and more particularly to apparatus of the kind described and claimed in my co-pending application Serial No. 586,188 filed September 5th, 1922.

One of the objects of my present invention 15 is the provision of apparatus so arranged that very hot water, for example, water of a temperature ranging from 170° to 205° F., may be obtained at the outlet faucets in a suitable consumption system 20 suitable for washing dishes, laundry purposes, etc. and at practically no additional operating expense.

A further object of my invention is the 25 provision of apparatus having two systems for delivering hot water and so arranged that water may be obtained from one of the systems at a temperature for example, 110° to 140° F., suitable for bathing and ordinary kitchen uses while very hot water 30 may be obtained from the other system suitable for washing dishes, laundry purposes, etc.

The invention consists in the novel constructions and arrangements to be hereinafter 35 described and claimed for carrying out the above stated objects and such other objects as will appear from the following description of a certain preferred embodiment illustrated in the accompanying drawing, 40 wherein—

Fig. 1 is a diagrammatic view of water heating apparatus embodying the principles of my invention; and

Fig. 2 is a longitudinal sectional view, on 45 an enlarged scale, of one of the water heaters preferably employed by me in the apparatus.

Like characters of reference designate like parts in both views.

Referring now to the drawings, and particularly to the diagram shown in Fig. 1 thereof, it will be seen that the apparatus includes a storage tank 5 supplied with cold water by means of a pipe 6 leading from a

source of supply and which terminates a 55 short distance above the bottom of the tank. The tank 5 is connected with a water heater, designated generally by the reference character 7, positioned in the heating boiler 8, by a plurality of pipes, including a substantially vertically disposed stand pipe 9, the upper end of which projects upwardly through and terminates a substantial distance above the bottom of the tank and the lower end of which is provided with a shut-off cock 10. The pipe 9 is provided with a fitting 11 from one side of which extends a horizontal pipe 12 connected by a fitting 13 with a relatively short pipe 14. The pipe 14 is connected by means of a fitting 15 with a horizontally extending pipe 16. A fitting 17 is provided on one end of the pipe 16 and is connected by a pipe 18 with the water heater 7. The pipe 19 is connected at its lower end to the water heater 7 and at its 75 upper end to a fitting 20. A horizontally extending pipe 21 is connected at one end to the fitting 20 and at the other end to a fitting 22, the latter being connected by a pipe 23 with the storage tank. 80

A hot water circulating consumption system including a pipe 24 extends to the various places at which the medium hot water is to be used, faucets 25 being provided to draw off the water when desired. The upper end of the pipe 24 is connected to a return pipe 26 which is connected to the pipe 16 by means of a fitting 27. The lower end of the pipe 24 is connected by a plurality of pipes 28 with the pipe 29 which extends through the fitting 22 and the pipe 23 and into the storage tank 5, the lower end of said pipe 29 extending a substantial distance below the level at which the pipe 23 discharges into the tank. A recording thermometer 30 may be connected in the consumption system just described, if desired. A check valve 31 is preferably provided in the return pipe 26. A cold water supply pipe 32 ordinarily extends alongside the pipe 24 but, as this pipe forms no part of the apparatus, its various connections and outlets have not been illustrated. 95

A water heater, designated generally by the reference character 33, is also positioned in the boiler 8. A pipe 34 leads from the upper portion of the tank 5 and is connected to the upper end of a pipe 35 by a fitting 100

36. Fittings 37 and 38 and pipes 39 and 40 connect the pipe 35 with the heater 33. A pipe 41 leads from the heater 33 and is connected by a fitting 42 with a pipe 43.
- 5 A hot water consumption system leads from the pipe 43, said system in the present case including a pipe 44 which extends to the various places at which the very hot water is to be used, faucets 45 being provided to draw off the water when desired. The upper end of the pipe 44 may be connected to a return pipe 46, the latter pipe being connected to the pipe 35. A check valve 47 is preferably provided in the return pipe 46.
- 10 The water heaters 7 and 33 are preferably of the type shown in detail in Fig. 2. Each heater includes a cast hollow head 48 provided with a partition 49 which is formed so as to provide chambers 50 and 51 in the head. One wall of the chamber 50 is provided with an opening 52 and is threaded for the reception of the water inlet pipe, 18 or 40, as the case may be. One wall of the chamber 51 is provided with an opening
- 15 53 also threaded for the reception of the water discharge pipe 19 or 41, as the case may be. The inner side of the head 48 is provided with a flange 54 adapted to be placed against the face of the boiler and to be secured thereto by a plurality of cap screws. The flange 54 is provided with an opening 55 and is threaded for the reception of a relatively large pipe 56, which is formed of a non-corrosive substance the heat
- 20 conductivity of which is relatively high, for example, copper. The head of the heater is provided with an opening 57 so that communication is established between the chamber 51 and the pipe 56. The inner end of
- 25 the pipe 56 is closed by any suitable means, for example, a cap 58. The partition 49 is provided with an opening 59 which is substantially concentrically disposed with respect to the openings 57 and 55, and the pipe
- 30 56. The outer end of a relatively small pipe 60 is placed in the opening 59, said pipe being secured in the partition 49 in any desired manner, for example, by turning the outer end of the pipe over the adjacent portion of the partition. The pipe 60 extends inwardly into the pipe 56, the inner end of said pipe 60 being left open and terminating somewhat short of the end of the pipe 56. The pipe 60 is also preferably formed of a
- 35 non-corrosive substance the heat conductivity of which is relatively high, and, as the walls thereof are quite thin, the pipe is preferably formed of brass to give it the desired strength. The wall of the chamber 50 opposite the partition 49 is provided with an opening 61 threaded for the reception of a
- 40 plug 62. The incoming water flows into the chamber 50 thence through the small pipe 60 and is discharged into the inner end of the large pipe 56 where its direction of flow

is reversed, the water then flowing out of the pipe 56 into the chamber 51. The course of the water through the heater is indicated by the several arrows. As the pipe 56 of the heater is subject to the heating action of the heating medium surrounding it, said pipe is heated, and, consequently, the temperature of the water while passing through said pipe will be raised very considerably. The hot water flowing in the pipe 56 transmits heat to the pipe 60 and said last mentioned pipe is heated to a considerable extent. By this arrangement the temperature of the water is gradually raised as it enters the pipe 60, it being subjected to the greatest degree of heat while passing through the pipe 56. Since the heat conductivity of the pipes 56 and 60 is relatively high, the efficiency of the heater is also high.

Operation.—The cold water in the tank 5 flows to the heater 7 where its temperature is raised, the heated water from said heater being returned to the upper portion of the tank. There is a continuous circulation of the water from the tank, through the heater 7 back to the tank, the temperature of the water in the tank usually being from 110° to 140° F. There is also a continuous circulation of the medium hot water from the tank through the circulatory consumption system comprising the pipes 24 and 26, water from said system being suitable for bathing and ordinary kitchen uses. Since the return pipe 26 is connected to the pipe leading to the heater 7, the feed water in said heater is tempered, thus increasing the efficiency of the apparatus. It will be noted that the pipe 29 is provided with a port 29^a which is so located that communication is established between said pipe and the upper portion of the chamber in the fitting 22. This arrangement prevents a column of air being trapped in the pipe 23, the fitting 22 and pipe 21 because in drawing water from the pipe 24, any air present in the pipe 23, fitting 22 or pipe 21 will be drawn through the port 29^a, thus insuring free circulation of the water through the pipes 21 and 23. By connecting the heater 33 in the manner heretofore described, the hot water in the upper portion of the tank flows to the heater 33 where it is further heated, its temperature, when it leaves said heater, ordinarily ranging from 170° to 205° F. The very hot water circulates from the heater 33 through the pipes 41, 43, the consumption pipe 44 and the return pipe 46.

Apparatus embodying the principles of my invention has been found to be very efficient in operation and satisfactory in service. The only appreciable additional expense is in installation because the amount of fuel used in the boiler to step-up or boost the temperature of the water is practically negligible. It will be obvious to those

skilled in the art, in those cases where very hot water only is desired, that the circulatory system comprising the pipes 24 and 26 may be done away with. The return pipe 46, which is connected to the consumption pipe 44, may be omitted, but in such case it is necessary to permit the water standing in the pipe 44 to run out before the very hot water is obtainable.

10 I do not intend to limit my invention to the details of construction shown and described, except only in so far as certain of the appended claims are specifically so limited, as it will be obvious that modifications 15 may be made without departing from the principles of my invention.

I claim:

1. In combination with a receptacle containing a heating medium, two water heaters 20 positioned in said receptacle in such manner that they are subject to the heating action of said medium, a storage tank, means connecting said tank with one of said heaters and so arranged that a supply of medium 25 hot water is maintained in said tank, means for supplying medium hot water from said tank to the other of said heaters, and a delivery pipe connected with said last-named heater.

30 2. In combination with a receptacle containing a heating medium, two water heaters positioned in said receptacle in such manner that they are subject to the heating action of said medium, a storage tank, means connecting said tank with one of said heaters and so arranged that a supply of medium hot water 35 is maintained in said tank, means for supplying medium hot water from said tank to the other of said heaters, and a circulating 40 consumption system connected with said last-named heater.

3. In combination with a receptacle containing a heating medium, two water heaters 45 positioned in said receptacle in such manner that they are subject to the heating action of said medium, a storage tank connected with a source of water supply, a pipe leading from the lower portion of said tank to one of said heaters, a pipe leading from said 50 last-named heater to the upper portion of said tank, a pipe leading from the upper portion of said tank to the other of said heaters, and a delivery pipe connected with said last-named heater.

55 4. In combination with a receptacle containing a heating medium, two water heaters positioned in said receptacle in such manner that they are subject to the heating action of said medium, a storage tank connected with a source of water supply, a pipe leading from the lower portion of said tank to one of said heaters, a pipe leading from said last-named heater to the upper portion of said tank, a pipe leading from the upper portion of said 60 tank to the other of said heaters, and a cir-

culating consumption system connected with said last-named heater.

5. In combination with a receptacle containing a heating medium, two water heaters 70 positioned in said receptacle in such manner that they are subject to the heating action of said medium, water supply means leading to one of said heaters, water circulating means leading from the heater connected to said water supply means to the other of said heaters, and a delivery pipe connected with said last-named heater.

6. In combination with a receptacle containing a heating medium, two water heaters 80 positioned in said receptacle in such manner that they are subject to the heating action of said medium, water supply means leading to one of said heaters, water circulating means leading from the heater connected to said water supply means to the 85 other of said heaters, and a circulating consumption system connected with said last-named heater.

7. In combination with a receptacle containing a heating medium, two water heaters 90 positioned in said receptacle in such manner that they are subject to the heating action of said medium, water supply means leading to one of said heaters, a circulating 95 consumption system connected with the heater connected to said water supply means, water circulating means leading from the heater connected with said water supply means to the other of said heaters, and a delivery pipe connected with said last-named 100 heater.

8. In combination with a receptacle containing a heating medium, two water heaters positioned in said receptacle in such manner that they are subject to the heating action of 105 said medium, water supply means leading to one of said heaters, a circulating consumption system connected with the heater connected to said water supply means, water circulating means leading from the heater connected with said water supply means to the other of said heaters, and a circulating consumption system connected with said last-named 110 heater.

9. In combination with a receptacle containing a heating medium, a water heater 115 positioned in said receptacle in such manner that it is subject to the heating action of said medium, storage means connected to a source of water supply, conduit means leading from said storage means to said heater, a pipe leading from said heater to said storage means, a hot water circulating system including a pipe leading from said storage means and having outlet means and a return pipe leading from said second-named pipe back to one of the two means first named, a second heater positioned in said receptacle in such manner that it is also subject to the heating action of said medium, a 120 125 130

- pipe leading from said storage means to said second heater and a delivery pipe connected with said second heater.
10. In combination with a receptacle containing a heating medium, a water heater positioned in said receptacle in such manner that it is subject to the heating action of said medium, storage means connected to a source of water supply, conduit means leading from said storage means to said heater, a pipe leading from said heater to said storage means, a hot water circulating system including a pipe leading from said storage means and having outlet means and a return pipe leading from said second named pipe back to one of the two means first named, a second heater positioned in said receptacle in such manner that it is also subject to the heating action of said medium, a pipe leading from said storage means to said second heater and a circulating consumption system connected with said last-named heater.
11. In combination with a receptacle containing a heating medium, a water heater positioned in said receptacle in such manner that it is subject to the heating action of said medium, storage means connected to a source of water supply, conduit means leading from the lower portion of said storage means to said heater, a pipe leading from said heater to the upper portion of said storage means, a hot water circulating system including a pipe leading from the upper portion of said storage means and having outlet means and a return pipe leading from said second-named pipe back to one of the two means first named, a second heater positioned in said receptacle in such manner that it is also subject to the heating action of said medium, a pipe leading from the upper portion of said storage means to said second heater, and a delivery pipe connected with said second heater.
12. In combination with a receptacle containing a heating medium, a water heater positioned in said receptacle in such manner that it is subject to the heating action of said medium, storage means connected to a source of water supply, conduit means leading from the lower portion of said storage means to said heater, a pipe leading from said heater to the upper portion of said storage means, a hot water circulating system including a pipe leading from the upper portion of said storage means and having outlet means and a return pipe leading from said second-named pipe back to one of the two means first named, a second heater positioned in said receptacle in such manner that it is also subject to the heating action of said medium, a pipe leading from the upper portion of said storage means to said second heater, and a circulating consumption system connected with said last-named heater.
13. In combination with a receptacle containing a heating medium, a water heater positioned in said receptacle in such manner that it is subject to the heating action of said medium, storage means connected to a source of water supply, conduit means leading from the lower portion of said storage means to said heater, a pipe leading from said heater and arranged so that water flowing therein must discharge into the upper portion of said storage means, a hot water circulating system including a pipe having controlled outlet means, said second-named pipe leading from the upper portion of said storage means and having its intake end sufficiently remote from the discharge end of said first-named pipe that water flowing into said second-named pipe must be taken from the supply in said storage means, and a return pipe leading from the discharge end of said second-named pipe that water flowing into said second-named pipe must be taken from the supply in said storage means, and a return pipe leading from the discharge end of said second-named pipe back to one of the two means first named, a second heater positioned in said receptacle in such manner that it also is subject to the heating action of said medium, a pipe leading from the upper portion of said storage means to said second heater, and a delivery pipe connected with said second heater.
14. In combination with a receptacle containing a heating medium, a water heater positioned in said receptacle in such manner that it is subject to the heating action of said medium, storage means connected to a source of water supply, conduit means leading from the lower portion of said storage means to said heater, a pipe leading from said heater and arranged so that water flowing therein must discharge into the upper portion of said storage means, a hot water circulating system including a pipe having controlled outlet means, said second-named pipe leading from the upper portion of said storage means and having its intake end sufficiently remote from the discharge end of said first-named pipe that water flowing into said second-named pipe must be taken from the supply in said storage means, and a return pipe leading from the discharge end of said second-named pipe back to one of the two means first named, a second heater positioned in said receptacle in such manner that it also is subject to the heating action of said medium, a pipe leading from the upper portion of said storage means to said second heater, and a circulating consumption system connected with said last-named heater.
